CLAIM

The ornamental design for exercise equipment with tread, as shown and described.

DESCRIPTION

FIG. 1 is a top perspective view of exercise equipment with tread;

FIG. 2 is a bottom perspective view thereof;

FIG. 3 is a top plan view thereof;

FIG. 4 is a rear elevational view thereof;

FIG. 5 is a front elevational view thereof;

FIG. 6 is a bottom plan view thereof;

FIG. 7 is a right-side elevational view thereof; and,

FIG. 8 is a left-side elevational view thereof.

The broken lines in the drawings form no part of the claimed design.

1 Claim, 3 Drawing Sheets
